UNITED STATES PATENT OFFICE.

ERNEST E. KRENGEL AND WILLIAM G. MCLENNAN, OF NEZPERCE, IDAHO.

COLD-AXLE SETTER.

No. 820,503.

Specification of Letters Patent.

Patented May 15, 1906.

Application filed January 23, 1906. Serial No. 297,718.

To all whom it may concern:

Be it known that we, ERNEST E. KRENGEL and WILLIAM G. MCLENNAN, citizens of the United States of America, and residents of 5 Nezperce, county of Nez Perce, State of Idaho, have invented certain new and useful Improvements in Cold-Axle Setters, of which the following is a full and clear specification, reference being had to the accompanying 10 drawings, in which—

Figure 1 is a perspective view showing our device applied to an axle; Fig. 2, an end view of the device on the axle; Fig. 3, a detail perspective view of the lever or bar; Fig. 4, a detail perspective view of the shiftable fulcrum; Fig. 5, a detail perspective view of the hook, 15 and Fig. 6 a detail perspective view of the gage parts separated.

The object of this invention is to provide a 20 simple and strong implement for straightening axles without heating them and without removing them from the vehicle, as more fully hereinafter set forth.

To the accomplishment of this object and 25 such others as may hereinafter appear the invention consists of the parts and combination of parts hereinafter fully described, and particularly pointed out in the appended claims, reference being had to the accompanying 30 drawings, forming a part of this specification, in which the same reference characters designate like parts throughout the several views.

Referring to the drawings by reference 35 characters, A designates a strong metal bar or lever which is provided along its under side with a central longitudinal strengthening-rib a, which makes the bar substantially T-shaped in cross-section. In the forward 40 end of the web portion a is formed a hole a' for the reception of the pivot-bolt b' of a yoke or loop B, which embraces the forward end of the bar and which has its lower end b made narrower in order to closely embrace the 45 web portion a of the bar. In the upper end of this yoke is mounted a screw C, provided at its upper end with a hand cross-bar c and having swiveled to its lower end a bearing-block c', which block is adapted to slide be- 50 tween the vertical bars of the yoke.

Mounted to slide on the bar is a fulcrum-block D, whose upper edge is tapered and whose lower side is provided with a pair of flanges d, which embrace the opposite edges 55 of the bar. A set-screw d' may be mounted on the fulcrum-block to hold it in its adjusted

position and to prevent it being shifted while in operation or sliding off the bar when not in use. At the rear end of the bar is mounted a 60 hook E, which is provided with a hook portion e, adapted to extend over the upper side of the axle. This hook is also provided with a plate e', which rests upon the upper side of the bar, and with a pair of inwardly-extending flanges e'', which engage 65 under the opposite edges of the bar and confine the hook to the bar, but permit it to slide lengthwise thereof. A set-screw e''' may be provided to lock a hook at its adjusted point and prevent it shifting while in use or sliding 70 off the bar when not in use.

The device is applied to the axle as shown in Fig. 1, and when the hook and the fulcrum-block are properly adjusted it is simply necessary to force down the bearing-block c' upon 75 the spindle f of the axle. The yoke B is swung up over the end of the spindle after the hook e is engaged over the main part of the axle. It will be observed that the hook and the fulcrum-block may be adjusted readily 80 on the bar and, further, that by reason of the fact that they are attached to the bar the device may be applied to the axle very readily. The shape of the bar in cross-section gives it great strength with a minimum of 85 weight and at the same time affords a convenient arrangement of oppositely-extending flanges on which the fulcrum-block and the hook may be mounted.

In order that the angle of the spindle may 90 be accurately determined during the act of bending it, we mount in the loop a gage-finger G, whose squared shank g works through a vertical slot b'' in one of the uprights of the loop, the gage being held in its adjusted position by a winged nut H, tapped on a threaded extension g' of the shank g, and bearing against the outer side of the bar of the loop through the medium of a washer.

What we claim, and desire to secure by 100 Letters Patent, is—

1. In a device of the class set forth, the combination of a bar having oppositely-extending longitudinal flanges along its upper edge and a central depending longitudinal 105 flange, a hook slidably attached to the opposite longitudinal flanges, a fulcrum-block also slidably attached to said flange, and a spindle-engaging device consisting of a loop having vertical side bars embracing the side 110 flanges of the bar and a reduced lower end embracing the central flange of the bar, a

pivot-bolt extending through the reduced portion and the intermediate flange, a slideable bearing-block adapted to slide vertically between the side members of the loop, and a screw mounted in the upper end of the loop.

2. In a device of the class set forth, the combination of a bar carrying a slideable fulcrum-block and a slideable hook for the purposes set forth, a spindle-engaging member consisting of a loop pivoted to the forward end of the bar and having parallel side members, a pressure-block working between the side members and a screw for operating this

block, and a gage-finger extending across the loop under the bearing-block and adjustable longitudinally on one of the side members of the loop. 15

In testimony whereof we hereunto affix our signatures, in the presence of two witnesses, this 12th day of January, 1906.

ERNEST E. KRENGEL.
WILLIAM G. McLENNAN.
